UNITED STATES PATENT OFFICE.

MILES C. HOLDEN AND FRANKLIN G. NEAL, OF SPRINGFIELD, MASSACHUSETTS; SAID NEAL ASSIGNOR TO SAID HOLDEN.

BOOK-COVER.

1,284,896.

Specification of Letters Patent. Patented Nov. 12, 1918.

Application filed June 5, 1916. Serial No. 101,752.

To all whom it may concern:

Be it known that we, MILES C. HOLDEN and FRANKLIN G. NEAL, citizens of the United States of America, and residing at 5 Springfield, in the county of Hampden and State of Massachusetts, have invented certain new and useful Improvements in Book-Covers, of which the following is a specification.

10 The invention relates to book covers and particularly to improvements in covers of the type disclosed in U. S. Letters Patent No. 779,161, granted January 3, 1905, to George W. Holden.

15 The patent referred to discloses a book cover which is particularly adapted for books of varying dimensions and is so constructed that one size of blank can be used for all the ordinary sizes of books within a 20 given range. While such covers have proved generally satisfactory in accomplishing the purpose for which they were intended, it has been found that, when the cover is used with books of certain sizes, it sometimes be- 25 comes torn after prolonged use due to the repeated opening and closing of the book. The difficulty has been found to be due in part to lack of sufficient flexibility in that portion of the blank, which covers the back 30 of the book, so that the said portion often fails to bend smoothly when the book is opened. The tendency is for the cover to crease along one or more lines and eventually to tear at the creased portions. This 35 difficulty is accentuated by the construction of the central upper tongue, which is of fixed width and is adapted to be turned in behind the back of the book to act as a reinforcement. It will be seen that, when books hav- 40 ing backs narrower than the tongue are cov- ered, a portion of the inturned tongue pro- jects behind one cover of the book which prevents free bending at the desired point and causes eventually a tearing of the cover 45 at one or both ends of the tongue. This invention is concerned particularly with the elimination of the difficulties above set forth.

An object of the invention is to provide in a book cover of the character described, 50 an upper tongue intermediate the two top flaps which tongue is of a width sufficient

to overlie the backs of the largest books encountered but has a series of scored or perforated lines parallel with one edge of the tongue along which the tongue may be conveniently severed to fit books having smaller backs.

Another object is to provide a book cover of the class described having its central portion scored with a series of parallel lines 55 preferably on the inside of the cover to form a flexible portion which will readily conform to the back of the book and will bend smoothly along the proper lines when the book is opened and closed.

Other objects and advantages will appear in the description to follow and in the annexed claims.

For the purpose of illustrating one manner in which the invention may be practised, a single preferred embodiment there- 70 of is shown in the accompanying drawing in which the figure shows a plan view of the unfolded blank.

As shown in this drawing, the blank com- 75 prises a substantially rectangular body por- tion 1, which is adapted to extend from the edge of one cover of the book, across the back thereof and to the edge of the other cover, whereby the book may be completely 80 covered. The end flaps 2, upper and lower flaps 3 and 4, respectively, and the lower central tongue 5 project from the body por- 85 tion 1 in a manner substantially the same as disclosed in the above identified patent. One end flap 2 is inturned as is also the left hand lower flap 4 which is pasted to flap 2 in the usual manner. Flaps 3 and the right hand flap 4 are provided with gummed por- 90 tions 6, whereby they may be secured to the end flaps 2 after the blank has been folded to fit the book, as will later appear.

An upper tongue 7 is formed between flaps 3 by cuts 8 and preferably perforations or scorings 9 are provided as prolongations 95 of the cuts 8, so that the length of the tongue, which is adapted to be inturned, may be varied to accommodate books of varying heights. The width of tongue 7, that is the distance between cuts 8, is gaged 100 to fit the back of the thickest book ordi- narily encountered but in order that tongue

7 may be varied in width to accommodate thinner books a series of spaced scored or perforated lines 10 are made in the tongue parallel to one edge thereof. Thus, by tearing along the left hand line 10, the tongue obtained will be of suitable width for the thinnest book customarily found and by tearing along other lines 10 books of intermediate sizes may be fitted. The entire 10 central portion of the blank, including both tongues 5 and 7, is also scored vertically preferably on its inner surface along a series of closely spaced parallel lines 11, which scorings cover substantially the entire width 15 of tongue 7. The score marks 11 may be formed in any suitable manner as by partially cutting the blank or by ruled indentations for example. They are, however, preferably formed on the inner surface of the 20 blank, not only for the sake of providing a neat smooth exterior surface, but also because the scorings thus formed permit flexibility in the desired direction, that is, when the book is opened.

25 The manner of covering a book with the blank cover disclosed will now be described assuming that the open book is represented by the rectangle 12 and that the thickness of the closed book is represented 30 by the dimension 13. One cover of the open book is slipped in and nested under the already inturned flaps 2 and 4 and the other flap 2 is folded along the edge of the other cover. The book is next closed to determine 35 its thickness and the perforated line 10 best accommodated to fit the back of the book is selected, as, for example, the left hand line 10 in the figure. The book is then opened, the tongue severed along the selected line 10, 40 and the entire tongue 7 is inturned along the top edge of the book. Tongue 5 is similarly inturned along the bottom edge of the book. Should the height of the book be less than that indicated by rectangle 12, the cuts 45 8 and left hand line 10 may be prolonged along the extensions 9. The upper flaps 3 and lower flap 4 are next inturned and gummed to the end flap 2 which completes the covering operation.

50 In using the book cover, as heretofore formed, the portion of the blank overlying the back of the book had no more flexibility than any other portion. Moreover, with a book of the thickness indicated by dimension 55 13, a portion of tongue 7 (that between left hand line 10 and right hand line 8) extended beyond the back of the book. Obviously, when the book so covered is opened, the cover bends along substantially vertical lines from the base of cuts 8 for the latter 60 form weak points and establish a natural line of bending. Now, when the central portion of the blank is not particularly flexible, it does not bend readily in a smooth 65 curve, when the book is opened, but on the

contrary tends to remain substantially flat. For example, assume that the right hand cover of the book is swung back, the blank up to right hand line 8 is firmly held to the cover of the book as is also the corresponding part of the blank on the left hand cover. The intermediate portion, namely, between the cuts 8, must be thrown outwardly as the cover of the book is opened but the blank, bending only slightly at the base of 70 right hand cut 8, tends to push the left hand cover, which, however, is firmly held to the book. Thus, the tendency is for the pushing action described to tear the blank at the base of left hand cut 8. By making the central 75 portion of the blank flexible, as by scoring, the tearing tendency is reduced since the tongue and portions therebelow will bend into a smooth curve. To completely prevent all possibility of tearing as described 80 the tongue 7 is cut to fit the back of the book by tearing along perforations 10. Thus, the weak points purposely employed to locate the lines of bending are arranged 85 to lie coincident with the edges of the closed 90 book.

Thus, we have provided an improved book cover which is characterized by provision for extended life under prolonged service. It is recognized that modifications 95 may be made in the structure herein described for illustrative purposes without departing from the scope of the invention which is defined by the appended claims rather than by the foregoing description of 100 one preferred form.

What we claim is—

1. A book cover composed of a single piece of paper having a substantially rectangular body portion and integral flaps on 105 the edges of said body, the upper of said flaps being cut along two converging lines to form a substantially central tongue, the latter being weakened along a plurality of spaced lines so that the tongue may be 110 readily severed along any of said lines by tearing, whereby the width of said tongue may be readily varied to conform to the thickness of the book to be covered.

2. A book cover composed of a single 115 piece of paper having a substantially rectangular body portion and integral flaps on the edges of said body portion, the upper of said flaps being cut by two converging lines to form a substantially central tongue, the 120 latter and the portion of the blank therebelow being scored along a series of spaced parallel lines extending vertically from the top of the tongue to the bottom of the lower flap, whereby the portion of the blank overlying the back of the book may be bent smoothly as the book is opened and closed.

3. A book cover composed of a single piece of paper having a substantially rectangular body portion and integral flaps on 130

the edges of said body portion, the upper of
said flaps being cut along two converging
lines to form a substantially central tongue,
the latter being weakened between said cuts
5 along a plurality of spaced parallel lines,
whereby the width of tongue may be con-
veniently varied as desired, said tongue and

the portion of the blank therebelow being
scored on its inner surface along a series of
spaced parallel lines which extend from the 10
top of the tongue to the bottom of the lower
flap.
